CLAIM

(21) Appl. No.: **29/168,843**

The ornamental design for an overhead housing for entertainment devices to be used by rearseat passengers in a wheeled vehicle, as shown and described.

(22) Filed: **Oct. 8, 2002**

DESCRIPTION

(51) LOC (7) Cl. **12-16**
(52) U.S. Cl. **D12/418**
(58) Field of Search D12/415, 418,
D12/400; D14/124, 126, 129, 113, 132-133,
100; 296/37.1-37.8, 70; 224/311, 539;
180/90; 439/34

(56) **References Cited**

FIG. 1 is a perspective view of an “overhead housing for entertainment devices to be used by rearseat passengers in a wheeled vehicle,” showing my new design as it would be seen by a seated passenger looking upwardly at the housing; FIG. 2 is a bottom plan view thereof; FIG. 3 is a rear elevational view thereof; FIG. 4 is a front elevational view thereof; FIG. 5 is a right side elevational view thereof, with the left side elevational view being a mirror image thereof; FIG. 6 is a cross-sectional view of the housing through the cutting plane indicated by the lines 6—6 in FIG. 2; and, FIG. 7 is a cross-sectional view of the housing through the cutting plane indicated by the lines 7—7 in FIG. 2. A top view of the housing has no ornamental distinctive features.

FIGS. 2-7 are shown on a reduced scale compared to that of FIG. 1.
